UNITED STATES PATENT OFFICE.

JOHN ATKINSON STAPLES, OF NEWBURGH, NEW YORK.

FOOT-OPERATED CONTROL DEVICE.

1,080,936.

Specification of Letters Patent.

Patented Dec. 9, 1913.

Application filed June 10, 1912. Serial No. 702,900.

To all whom it may concern:

Be it known that I, JOHN A. STAPLES, a citizen of the United States, residing at Newburgh, in the county of Orange and State 5 of New York, have invented certain new and useful Improvements in Foot-Operated Control Devices; and I do hereby declare the following to be a full, clear, and exact description of the invention, such as will 10 enable others skilled in the art to which it appertains to make and use the same.

My invention consists in the novel features hereinafter described, reference being had to the accompanying drawings in 15 which I have shown the preferred embodiment of my invention and several modifications thereof selected by me for purposes of illustration and the said invention is fully disclosed in the following description 20 and claims.

In the said drawings, Figure 1 represents a perspective view, partly in section, of an embodiment of my invention in its preferred form, adapted for use as an "accelerator" for controlling the feed of gasolene or explosive mixture to the motor of an automobile. Fig. 2 is a top plan view of the same. Fig. 3 is a longitudinal sectional view of the device parts being shown in elevation. Fig. 4 is a detail perspective of the 25 pedal with parts detached. Fig. 5 is a transverse sectional view of the device parts being shown in elevation. Fig. 6, a top plan view illustrating a modified embodiment of my invention. Figs. 7, 8 and 9 are respectively a plan, side elevation, and section of a further modification of my invention.

In the use of vehicles driven by prime 40 motors, it is desirable that a portion of the control shall be capable of being exercised by the foot of the driver, as his hands are ordinarily fully occupied in the management of the steering wheel and change speed 45 lever. In vehicles driven by explosion engines it is therefore usual to provide a foot operated lever, or treadle operatively connected for example with a valve controlling the supply of gasolene to the engine, in 50 order that the operator may increase or diminish the supply of fuel in accordance with road conditions, by a movement of his foot. These devices are termed "accelerators" and the foot operated lever thereof is ordinarily 55 moved vertically or laterally by a pressure of the toe, against the action of a spring.

which is employed to return the lever to normal position. This operation necessitates a more or less accurate balancing of the foot, usually upon the heel thereof, the variations in fuel supply being obtained by variations in pressure on the lever. The necessity of so balancing the foot occasions a considerable strain on the muscles of the foot and leg, which in long continued driving results in considerable fatigue and frequently in pain, and moreover the vertical oscillations of the vehicle body, as in passing over rough roads results in changes in the equilibrium of the driver's body, which is resisted by the pressure of his feet upon the floor, thus making him liable to involuntarily alter the adjustment of the control valve or device connected with the foot lever or accelerator and frequently causing an excess of fuel to be supplied to the engine at inopportune moments, occasioning the racing or stalling of the engine, and deposits of carbon in the cylinders and spark plugs.

The object of my invention is to provide a foot operated control device for vehicles on which the foot may rest with the entire weight at all times without in any way affecting the operation of the device and in which the portion of the foot not engaged by the device is raised from the floor or foot support only during the time that the device is being adjusted, the foot remaining at all other times firmly supported by the control device and contiguous flooring or foot support, in an easy and natural position. Thus all strain is removed from the foot and leg muscles; the driver can brace himself by means of the foot engaging my improved device, against jar and shock from the movements of the vehicle frame or body and without in any way disturbing the adjustment of the control device.

In the accompanying drawings Figs. 1 to 5 inclusive, I have shown an embodiment 100 of my invention selected by me for purposes of illustration and arranged for operating as an "accelerator" for explosive engine driven vehicles, being in this instance operatively connected with a valve for controlling the supply of gasolene, which may be constructed in any usual or preferred manner. I wish it to be understood, however, that I do not limit myself to the use of my improved device for controlling a gasolene 105 valve as it may be employed to operate a switch or rheostat lever, or other control de-

vice employed on an automobile or other vehicle, or for other purposes for which its use may be found advantageous.

In the preferred form or embodiment of my invention illustrated in Figs. 1 to 5 inclusive, 1 represents a foot plate, preferably of metal, and preferably wedge shaped, in longitudinal section, that is to say having a thin edge at the rear and increasing gradually in thickness toward the front, to conform to the upward curve at the front end of the sole of an ordinary shoe or boot, as indicated in Fig. 3, so that the toe portion of the foot of the operator may rest thereon without elevating the sole entirely or to any appreciable extent from the floor or foot support F. The plate 1 is pivotally mounted on a vertically disposed pivotal connection, located beneath and substantially perpendicular to said plate, it being in this instance rigidly attached to a pivotal stem 2 extending down through the floor, said stem being provided with a laterally projecting arm or lever 3, which is preferably provided with a plurality of holes 4 or other attaching means to facilitate adjustment between it and the devices connected therewith. The pivot stem 2 is preferably located within the confines of the foot, and I prefer to locate it substantially under the ball of the foot. The plate 1 is provided with means for engaging the foot on opposite sides, and in my preferred embodiment these means consist of raised side pieces 5 and 6, as shown, for engaging opposite sides of the sole portion. I prefer to provide at least one of these side pieces with means for so engaging the shoe or foot of the operator as to prevent the longitudinal movement of the foot in both directions with respect to the plate 1. In the present instance the side piece 5 which is on what I term the "pressure side" of the plate, is preferably made integral with, or rigidly and permanently secured to, the plate 1, and extends preferably in a curve beyond the rear edge of plate 1 and beyond the widest portion of the sole of the operator's foot to give the foot a better leverage on the plate and to prevent the rearward movement of the foot with respect to the plate. The curved shape of the side piece 6 also tends to hold the foot from moving rearwardly or forwardly, and the inclined upper face of plate 1 also tends to prevent the foot from slipping forward. The side piece 6 is preferably adjustable laterally to accommodate differences in the width of the toe of shoes or boots worn by different drivers. As shown in Fig. 4 the side piece 6 is provided with dowel pins 7, engaging transversely disposed guiding apertures in the plate 1 and a set screw 8 engaging a longitudinally disposed threaded aperture in the plate 1 communicating with one of the said guiding apertures, is em-

ployed to secure the side piece 6 in its adjusted position. I do not limit myself, however, to this specific means for adjustment, and if desired the adjusting means may be omitted, if the side plates are separated sufficiently, as the twisting movement of the foot will naturally throw the toe portion near its extremity into engagement with the side plate 6, even if the space between it and the side piece 5 is greater than the width of the shoe sole at that point. 75

The arm 3 is connected in any suitable manner with the instrumentality which is to be controlled. In this instance I have shown it connected by a link 9 with an arm 10 connected with a valve stem 11 of a gasoline controlling valve 12, and said arm 3 is also provided with a retracting spring 13 which is secured at its other end to a stationary part of the vehicle in this instance to the side sill 14 (see Fig. 2) by an eye bolt 15, or other suitable fastening. I also prefer to provide a stop for arresting the return movement of the plate, stem and arm, under the influence of the retracting spring, which 85 comprises in this instance a collar 16, provided with a stop lug 17, to engage a fixed stop or pin 18 secured to the under side of the floor or foot support, but I do not limit myself to the particular form of stop herein 90 shown and described. 95

In the use of the device the operator places his foot in engagement with the plate 1, the toe portion of the foot resting on said plate, between the side pieces 5 and 6, the heel resting upon the floor or foot support F, thus giving a firm support for the entire foot, on which any desired amount of pressure may be exerted, while the foot rests in a perfectly easy and natural position without strain on the foot or leg muscles. To further open the valve 12 to increase the fuel supply the operator will swing the heel to the right more or less as required, against the pressure of the spring 13, preferably 100 slightly raising the heel from the floor during the instant of moving it, and then replacing the heel on the floor (or the heel may be simply slid laterally without raising it if preferred). To partially close the valve and reduce the fuel supply the heel is swung to the left with the pressure of the spring. The frictional engagement of the heel with the floor will hold the plate and connected parts in adjusted position, thus 105 relieving the operator from the necessity of keeping up the lateral pressure, and enabling him to rest his weight firmly on the whole foot at all times, with the exception of the instant when he may move his heel laterally and even then he may rest his weight on the toe, and against the plate 1, to steady himself, without affecting the 110 operation of the device. As no locking means is provided for holding the plate in its 115 adjusted position. 120

justed position, other than the frictional engagement of the portion of the foot not engaged by the plate, with the foot supporting board or floor, it is not necessary to raise any part of the foot from the floor to make a quick change of adjustment, and this is a very desirable feature of the device. It is obvious therefore that in driving over rough roads the steady and evenly regulated feed of fuel may be maintained and the driver is relieved from the strain both mental and physical of endeavoring to balance his foot against the resistance of a spring and keeping an accurate and adjusted pressure upon the foot engaging part, notwithstanding the jarring of the vehicle body. As the weight of the foot is at all times firmly upon the plate 1, and is further held laterally by the side pieces 5 and 6, it is practically impossible that the foot shall be thrown out of operative engagement with the plate 1, and the flooring, no matter how much the vehicle may be jarred in passing over rough or uneven roads. It is to be understood that a portion of one end of the foot only engages the plate, which end of the foot becomes practically integral with the plate, the free end of the foot resting flat upon the foot-board or flooring in stable position at all times except when a change of adjustment is being effected.

In Fig. 6 I have shown a modified form or embodiment of the device in which the pivoted plate is designed to be engaged by the heel and operated by swinging the toe laterally. In this figure 21 is the plate, 22 the pivot stem, 23 the arm or lever provided with a plurality of securing apertures 24, and 25, 26 are the side plates for retaining the heel to afford the necessary engagement between the heel and plate to effect the rotation of the latter. The side plate 26 is shown as being laterally adjustable and is held in adjusted position by a set screw 28.

In Figs. 7, 8 and 9 I have shown a further modification of the device, in which the wedge shaped plate 51 is secured to the pivot stem 52, and provided with a pair of laterally adjustable and rearwardly extending arms or side-pieces 53, 56 provided at their rear ends with angular clips 57, 58 to engage the sides of the boot or shoe sole. The arms 53, 56, are provided with right and left hand screws respectively 59 and 60, extending laterally into apertures in the sides of the wedge plate, and engaging a central nut 61 which is reversely threaded so that a turn of said nut will draw said arms closer together or move them farther apart, as desired to adjust the device to the width of the operator's foot.

What I claim and desire to secure by Letters Patent is:

1. A foot operated control device for automobiles comprising a torsionally movable

pedal, adapted to engage a portion of the bottom of the foot of an operator, said pedal being of less length than the foot to permit portions of the bottom thereof not engaged by said pedal to frictionally engage the adjacent flooring, said pedal being provided with means for connecting it to the foot for imparting a torsional movement to the pedal, a pivotal support for said pedal located beneath the same and substantially perpendicularly thereto, and means adapted to connect said pedal to the part to be controlled whereby said pedal may be operated by swinging the portion of the foot in engagement with the flooring laterally on a circle concentric with said pivotal axis, without raising any portion of the foot.

2. A foot operated control device for automobiles comprising a torsionally movable pedal having a supporting surface for engaging the sole portion of the foot of an operator, said pedal being of less length than the foot to permit the heel to frictionally engage the adjacent flooring, said pedal being provided with means for connecting it to the foot for imparting a torsional movement to the pedal, a pivotal support for the pedal disposed perpendicularly thereto, and located beneath, approximately, the portion of the supporting surface thereof which is engaged by the ball of the foot and means adapted to connect said pedal with the part to be controlled, whereby said pedal may be operated by swinging the heel laterally on a circle concentric with said pivotal support, without raising any portion of the foot.

3. A foot operated control device for automobiles comprising a torsionally movable pedal having a supporting surface for engaging the sole portion of the foot of an operator, said pedal being of less length than the foot to permit the heel to frictionally engage the adjacent flooring, said pedal being provided with means for connecting it to the foot for imparting a torsional movement to the pedal, a pivotal support for the pedal disposed perpendicularly thereto and located beneath, approximately, the portion of the supporting surface thereof which is engaged by the ball of the foot and means adapted to connect said pedal with the part to be controlled, whereby said pedal may be operated by swinging the heel laterally on a circle concentric with said pivotal support, without raising any portion of the foot, said pedal being provided with means for preventing the longitudinal movement of the foot with respect thereto.

4. A foot operated control device for automobiles, comprising a torsionally movable pedal having a supporting surface inclined to a plane perpendicular to its axis of oscillation adapted to be engaged by the sole portion of the foot of an operator, and being

of less length than the foot to permit the heel to frictionally engage the adjacent flooring, said pedal being provided with laterally disposed portions projecting above the foot engaging surface for engaging lateral portions of the foot to impart a torsional movement to the pedal, a pivotal support for the pedal having its axis disposed perpendicularly to its lower face, and 5 located beneath approximately the portion of said supporting surface engaged by the ball of the foot, and means adapted to connect said pedal with the part to be controlled thereby, whereby said pedal may be 10 operated by swinging the heel laterally on a circle concentric with said pivotal support, without raising the foot.

5. A foot operated control device for automobiles comprising a torsionally movable 20 pedal having a supporting surface adapted to be engaged by the sole of the foot and being of less length than the foot to permit the heel to frictionally engage the adjacent flooring, a pivotal support for said pedal 25 having its axis disposed substantially perpendicularly thereto and located beneath approximately the portion of said supporting surface engaged by the ball of the foot, and means adapted to connect said pedal to the 30 part to be controlled, said pedal being provided with lateral opposed portions extending above said supporting surface, for enabling the foot to impart a torsional movement to the pedal, one of said projecting 35 portions being adjustable laterally with respect to the other.

6. A foot operated control device for automobiles comprising a torsionally movable 40 pedal having a supporting surface adapted to be engaged by the sole of the foot and being of less length than the foot to permit the heel to frictionally engage the adjacent flooring, a pivotal support for said pedal having its axis disposed substantially per-

pendicularly thereto and located beneath approximately the portion of said supporting surface engaged by the ball of the foot and means adapted to connect said pedal to the part to be controlled, said pedal being provided with lateral opposed portions extending above said supporting surface, for enabling the foot to impart a torsional movement to the pedal, one of said projecting portions being curved outwardly and extended rearwardly beyond the widest portion of the sole of the foot to prevent the longitudinal movement of the foot with respect to the pedal. 45

7. A foot operated control device for automobiles comprising a torsionally movable 60 pedal having a supporting surface adapted to be engaged by the sole of the foot and being of less length than the foot to permit the heel to frictionally engage the adjacent flooring, a pivotal support for said pedal 65 having its axis disposed substantially perpendicularly thereto and located beneath approximately the portion of said supporting surface engaged by the ball of the foot, and means adapted to connect said pedal being 70 provided with lateral opposed portions extending above said supporting surface, for enabling the foot to impart a torsional movement to the pedal, one of said projecting portions being adjustable laterally with 75 respect to the other, and one of said projecting portions being curved outwardly and extended rearwardly beyond the widest portion of the sole of the foot and beyond said pedal, to prevent the longitudinal 80 movement of the foot with respect to the pedal.

In testimony whereof I affix my signature, in the presence of two witnesses.
